(57) **CLAIM**

The ornamental design for an intra-uterine inserter as shown and described.

DESCRIPTION

FIG. 1 is a front-right side-bottom perspective view of an intra-uterine inserter, showing my new design in a first environment.

FIG. 2 is a front view thereof.

FIG. 3 is a rear view thereof.

FIG. 4 is a left side view thereof.

FIG. 5 is a top view thereof shown at an enlarged scale.

FIG. 6 is a bottom view thereof shown at an enlarged scale.

FIG. 7 is a front-right side-bottom perspective view of the intra-uterine inserter, showing our new design in a second environment due to a light upward movement of a knob.

FIG. 8 is a front view thereof.

FIG. 9 is a front view of the intra-uterine inserter, showing our new design in a third environment due to a further upward movement of the knob.

FIG. 10 is a left side view thereof.

FIG. 11 is a front-right side-bottom perspective view thereof.

FIG. 12 is a top view thereof shown at an enlarged scale.

FIG. 13 is a front view of the intra-uterine inserter, showing our new design in a fourth environment due to a further different position of the knob; and,

FIG. 14 is a front-right side-bottom perspective view thereof.

The broken lines in the Figures show portions of an intra-uterine inserter and environment that form no part of the claimed design.
